IMPEDANCE BOX

Leo Behr, Philadelphia, Pa., assignor to Leeds & Northrup Company, Philadelphia, Pa., a corporation of Pennsylvania

Application April 20, 1932, Serial No. 606,365

7 Claims. (Cl. 201—48)

My invention relates to impedance boxes, and particularly to resistance boxes used in precision measuring instruments or systems, and particularly for measurements of alternating currents 5 of low and high frequencies.

In accordance with my invention, the resistors are mounted upon a support which is movable to include a selected resistance or resistance section individually in circuit with conductors of 10 fixed length and position within the box, so that the reactive effects of the internal circuit of the box are low and remain substantially constant for different resistance settings.

More specifically in a multiple decade box, the 15 resistors of each decade are mounted upon a common movable support, and the conductors, including brushes, for connecting the selected resistors of the decades to each other and to the box terminals are all of fixed length and position.

My invention also resides in the features of construction, arrangement, and combination hereinafter described and claimed.

For an understanding of my invention, and 25 for illustration of several forms it may take, reference is to be had to the accompanying drawings in which:

Fig. 1 diagrammatically illustrates a measuring circuit utilizing a common form of resistance 30 box.

Fig. 2 is a diagram of the same circuit utilizing my new resistance box.

Fig. 3 is a bottom plan view of a six-decade box constructed in accordance with my invention.

Fig. 4 is a side elevation of Fig. 3.

Fig. 5 is a top plan view of the box of Fig. 3.

Fig. 6 illustrates another type of measuring circuit utilizing a modification of my invention.

Fig. 7 in perspective, illustrates an attenuator 40 resistance box constructed in accordance with my invention.

Figs. 8 and 9 illustrate vertical sectional and perspective views, respectively, of a contact brush used in connection with the structures of Figs. 45 2-5.

For a better understanding of my invention, the errors introduced by use of the old style resistance boxes, particularly in alternating current measurements, are first discussed.

Referring to Fig. 1, which illustrates a system 50 for determining the value of an unknown resistance by the substitution method, the magnitude of the unknown resistance X is determined by first setting the contact arms 1 and 2 of the resistance box B to their zero positions, and ad-

justing the capacity C until the meter A indicates that the circuit is in resonance. The resistance X is then excluded from circuit, as by replacing it with a bar or strap of negligible resistance, and the contact arms 1 and 2, of the resistance box B manipulated until the same reading of meter A is obtained. The value of resistance X is supposedly equal to the resistance introduced into the loop circuit by the movement of either or both of the contact arms 1 and 2 from their zero position. 5

However, with the box construction shown, the readings are not accurate because the change in positions of the arms 1 and 2 does more than insert resistance into the loop comprised of the 15 condenser C, ammeter A, the transformer secondary S, and conductors 3, 4, 5, 6, and 7. The change in setting also varies the inductance and/or capacity as well for reasons now given, and the error is different for different settings 20 and for different frequencies of the source II . With the contact arms 1 and 2 in their zero position, the length of the loop between the terminals 8 and 9 of the resistance box is equal to the length of conductors 5, 6 and 7 plus the length of 25 the contact arms 1 and 2. This path within the box possesses a certain inductance which is one of the factors determining the current through the ammeter A. Further the resistances $r1-r10$ associated with contact 1, are always connected 30 to one another by the conductors 10, and the same is true of resistance $R1-R10$ associated with contact 2 so that resistances not included in the circuit nevertheless exhibit capacitative effects which affect the reading of meter A. 35 Briefly, for every different setting of the contacts 1 and 2, the box not only introduces a known resistance into the measuring circuit, but also introduces spurious unknown and uncompensated inductance and capacity variations. 40

For example, with the contact arms in the position shown, the inductance between the terminals 8 and 9 of the box, and consequently of the entire loop circuit including condenser C, inductance S, conductors 3 and 4, etc., is increased by the inclusion of the several conductors 10 inter-connecting the resistors $r1$ to $r5$, and $R1$ to $R4$. The undesired and unavoidably interjected change in inductance is different for every combination of settings of the contact arms, and moreover the effect 45 of these many inductance changes upon the ammeter reading depends upon the frequency with which the measurements are being made. If the frequency of current generated or supplied by the source II is high, for example 10,000 to 50,000 50 55

cycles per second, or higher, the change of inductance effected by the change in setting of arms 1 and 2, has all the more effect upon the current through the ammeter, so that the calibrations of the box cannot be relied upon as giving the true value of resistance X . The matter is more complicated because of the fact that for the different settings of the resistance arms, the number of inactive resistances, and their capacity effects, also vary.

10 Briefly, with the prior type of resistance boxes, it is not possible to obtain accurate measurements in alternating current systems, particularly when the frequencies are high, because the spurious inductance and capacity of the internal circuit of the box is not constant but different for every different setting.

15 Referring to Fig. 2, the current path within the box B between its terminals 8 and 9 is always of fixed length and position. The resistors k_0 to k_{10} are mounted upon a movable support 12 and each is provided at its opposite ends with individual contacts 13 and 14. Each resistance is electrically independent of every other. As the support 12 is moved to the right, Fig. 2, resistors 20 of increasing magnitude are individually and selectively included in circuit between the fixed brushes 15 and 16. Similarly resistors K_0 to K_{10} are mounted upon a common support 17 which is movable to include the resistors individually and 25 selectively in circuit between the fixed brushes 25 and 18 which successively engage contacts 13' and 14'. The conductor 19 between brushes 16 and 18 is of fixed length and position. It is apparent 30 that with this arrangement, unlike Fig. 1, the circuit configuration is not changed for the different settings of the resistance box; the spurious inductance and capacity of the box, and of the circuit as a whole, remain substantially constant, and only the resistance in circuit is changed. 35 Consequently, with the box of Fig. 2, the readings are very accurate for all settings and throughout a substantial range of frequencies.

40 When the supports 12 and 17 are in their zero position, the conductors k_0 and K_0 of negligible resistance are connected between the pairs of stationary contacts 15-16 and 25-18. When the supports are moved to any other position the symmetry of the arrangement is not modified by inclusion of any additional conductors, as in the box 45 of Fig. 1, nor is there any change in capacity effects due to unused resistors hanging on to the resistances in circuit. Only one resistance of each section is in circuit at a time and it is not in any way electrically connected to any other resistance of that section.

45 The individual resistors are preferably of the low time constant type disclosed and claimed in copending applications Serial No. 586,518 and Serial No. 590,334, filed January 4, 1932, and February 2, 1932, respectively which have matured as Patents 1,972,499 and 1,972,720, respectively.

50 It is understood of course, that the values of resistance k_1 to k_{10} and K_1 to K_{10} in accordance with usual practice, are selected to afford a wide range in values, with small steps of change, for example, the resistances k_1 to k_{10} may increase by .1 ohm steps from .1 ohm to 1 ohm, and the resistances K_1 to K_{10} increase by 1 ohm steps from 1 to 10 ohms. Therefore, with this arrangement, 55 any resistance value from zero to 11 ohms may be obtained in .1 ohm steps. In other words, there are over one hundred different resistance settings. The same is true in the box shown in Fig. 1, but with that arrangement, there is also concurrently

effected as many different undesired inductance and capacity changes whereas in the arrangement shown in Fig. 2 the inductance and capacity remain substantially the same for all settings and only the resistance is changed.

60 It is understood, of course, that the use of my improved box B is not limited to a measuring circuit of the type shown in Figs. 1 and 2, but is of general application and may be used to advantage, in Wheatstone bridge circuits, potentiometer circuits, and the like, and in general, in all alternating current measuring or control circuits where it is desired that change in resistance shall not be accompanied by change in inductance or capacity. The conductors of the system or circuit external 15 to the resistance box should remain in fixed position, at least for any series of measurements, to preclude any change in the inductance and/or capacity of the entire circuit.

65 The box may, of course, be used in direct current measuring circuits so that its use is universal; i. e., it may be used either in direct current measuring systems or in alternating current systems utilizing widely differing frequencies.

70 The invention is all the more important as the number of box groups, or decades, is increased, for the number of possible variations of inductance and capacity follow the laws of permutations and combinations. For example, with a six-decade box, such as shown in Figs. 3 to 5, the number of possible different inductances and capacity changes introduced is incredibly high, for example, of the order of one million. It is apparent that it is practically impossible to calibrate a resistance box to take into account all 75 of the changes of inductance and capacity for all the different possible combinations of settings, even at one frequency, much less for a wide range of frequencies. The simple arrangement shown in Fig. 2 is capable of being expanded for use with any number of resistance box groups or 80 decades and avoids any need for the attempt to consider the effects of numerous changes in inductance and capacity.

85 Referring particularly to Fig. 4, the resistances of each group are mounted upon a rotatable support or drum 20, corresponding generally to the supports 12 or 17 of Fig. 2. The resistances R of each group are preferably arranged with their axes parallel to the shaft 21 upon which the drum is mounted. The series of contacts 13 90 angularly spaced at one end of the drum, are connected to the corresponding ends of the resistance R , while the contacts 14 angularly mounted upon the other end of the drum, are individually connected to the other ends of the resistances. As diagrammatically shown in Fig. 2, each resistance of a group or decade is provided with a pair of contacts, and is electrically independent of every other resistance of that section.

95 A fixed contact or brush 15, fastened for example, to panel 23 is adapted to be successively engaged by the lower set of contacts 13 as the first drum is rotated, while the brush 16, held in fixed position upon the supporting member 24 extending to the rear of panel 23, is adapted successively to engage the upper contacts 14. The relative positions of the contacts 13 and 14 is such that for any setting of the dial 23 they engage contacts 13 and 14 associated with the same resistance, as diagrammatically shown in Fig. 2.

100 The other end of brush 16 may engage the upper contacts 14 of the adjacent drum 20, form-

ing a short conductor 19 of fixed length and position between the adjacent resistance sections of the box. Similarly, the brush 25 secured to the rear of panel 23 forms a short path of fixed length 5 between the second and third drums, and so on, the brush 15', connected to terminal 8 of the box, engaging the lower contacts 13 of the last drum 20.

Briefly, rotation of knob 22 individually and 10 selectively includes resistors of the first group in circuit between the fixed brushes 15 and 16; rotation of knob 26 includes the resistances of the second group individually and selectively in circuit between the fixed contacts 18 and 25; 15 rotation of knob 27 introduces the resistances of the third drum individually and selectively in circuit between the fixed contact 25 and the brush 28 mounted upon a supporting member 29, and, as shown in Fig. 3, engaging the contacts 14 of the 20 two end drums, etc. The arrangement of the remaining brushes and drums is believed apparent from the foregoing description.

The number of drums or decades in series, or parallel, etc., can be increased to any number 25 desired to afford any range of resistance values.

Preferably, as shown most clearly in Figs. 8 and 9, the brushes 16, 25, etc., are so constructed that the circuit is not broken during the transition from one resistor to the next even though the 30 surfaces of the drum contacts 14 are or become irregular, or are not exactly in the same plane. More specifically, each brush comprises two superposed elements, as 16a and 16b, whose contact engaging faces or tips T and T₁ may be of 35 somewhat greater extent than the distance between adjacent drum-contacts 14, and the elements 16a and 16b are of different length so that their tips are staggered. Therefore, during the change in setting from one resistor to the next, one or the other of the tips T, T₁ is in engagement 40 with a contact 14. The contact arrangement is of particular utility in my one-impedance-per-step box to ensure that the circuit shall be continuous during the change from one resistor to the next.

The invention may also be applied to other types of resistance boxes, for example, attenuator boxes, in order that for each different setting, a 50 different resistance section, usually of several resistors, will be selectively included in the circuit, to the exclusion of all other sections of the box.

In the attenuator box shown in Fig. 6, certain of the sections, as sections 1 to 5, are of the H type, while the remainder are of the O type. As in the prior modification, all of the resistances of the several sections are mounted upon a movable support and the terminal contacts of the sections are arranged to engage the fixed brushes 40 or contacts 115, 116, 125, and 118. For each different setting of the box, only the resistances of a single section are included in the path between the input terminals and the output terminals of the box. The length and position of the paths 55 between the terminals remains constant, and there is no inductance or capacity variation introduced by the change in settings.

The construction shown in Fig. 7 is suitable for the attenuator arrangements shown in Fig. 6. 70 Upon the upper end of the terminal drum 20 are mounted two sets of contacts 31, 32, the outer row of which is adapted successively to engage fixed contact 115 and the inner row adapted successively to engage fixed contact 116. Both of the fixed 75 contacts may be secured to and mounted upon

the support 124 secured to and extending from the rear face of panel 123. The fixed contacts or brushes 125 and 128 similarly cooperate with two rows of contacts 30 and 33 arranged at the lower end of the drum. As the drum is rotated about its axis, by a suitable knob, or the like, the different attenuator sections are individually and selectively interposed between the input brushes 115, 116 and the output brushes 125 and 118, as more clearly shown in Fig. 9. Each resistance section is included in circuit to the exclusion of all other sections, and the attenuation is due solely to the resistance of the section, and not to inductance or capacity effects introduced by the change in setting. 15

It is to be understood that instead of resistances, inductances or condensers may be mounted upon the drum or drums of the box so that for different settings of the box, condensers or inductances will be individually included in circuit by conductors of fixed length and position. Further in a multiple decade box, the connections may be such that the selected impedance of one decade may be placed in parallel to the selected impedance of another decade. 20

For brevity in the appended claims, the term "resistance section" is used to mean either a single resistance, or a group of resistances connected to each other but independent of the remaining resistances. 25

What I claim is:

1. A resistance box suited for precision measurements at high frequencies of alternating current comprising a pair of rotatable supports, a group of resistors mounted on each of said supports with their axes substantially parallel with the axis of rotation of the support, a plurality of contacts at one end of each of said supports individually connected to corresponding terminals of the resistors, a second set of contacts at the other end of each of said supports individually connected to the other terminal of the resistors, stationary brushes each adapted successively to engage the contacts at one end of one of said supports, and a stationary brush whose opposite ends successively engage the corresponding contacts at the other ends of said supports. 45

2. A resistance box suited for precision measurements at high frequencies of alternating current comprising a plurality of units each comprising a rotatable drum, a series of angularly spaced contacts at each end of the drum, and a group of resistors each having a terminal connected to a contact at one end of the drum and another terminal connected to an individual contact 50 at the other end of the drum, terminals for said box, and an individual connection system of fixed configuration and position for including in series between said terminals a selected resistor of each of said groups comprising fixed brushes connected 55 to said terminals and adapted successively to engage the spaced contacts at one end of drums adjacent thereto, and fixed brush structure whose opposite ends successively engage the contacts at one end of adjacent drums. 65

3. A resistance box suited for precision measurements at high frequencies of alternating current comprising two fixed contacts, a fixed brush having each of its ends disposed in alignment with one of said contacts, a structure carrying a plurality of resistors and movable to interpose one of said resistors between one of said fixed contacts and the corresponding end of said brush, and a second structure carrying a plurality of resistors and movable to interpose one of said re- 70 75 75

- sistors between the other fixed contact and the other end of said brush, whereby the resistance in circuit between said fixed contacts may be varied without change of the circuit configuration.
5. An impedance box comprising a rotatable support, a group of impedances carried by said support, a group of contacts carried by said support and each connected to one of said impedances, brush structure for selectively including said impedances in circuit comprising superposed elements terminating in nested U-shaped tips whose contact-engaging faces are greater in extent than the spacing between adjacent contacts and spaced in the direction of relative motion of said contacts.
10. 4. An impedance box comprising a rotatable support, a group of impedances carried by said support, a group of contacts carried by said support and each connected to one of said impedances, brush structure for selectively including said impedances in circuit comprising superposed elements terminating in nested U-shaped tips whose contact-engaging faces are greater in extent than the spacing between adjacent contacts and spaced in the direction of relative motion of said contacts.
15. 5. A resistance box suited for precision measurements at high frequencies of alternating current comprising a plurality of movable supports, a group of individual resistance sections, conductors of fixed length and position within said box, means individual to said supports for moving them to include in circuit with said conductors an individual section of each of said groups, and means cooperating with said support-moving means to indicate externally of the box which of said sections are in circuit.
6. A resistance box suited for precision measurements at high frequencies of alternating current comprising a plurality of movable supports, a group of resistors carried by each of said supports, conductors of fixed length and position within said box, means individual to said supports for moving them to include in circuit with said conductors one resistor of each of said groups, and means cooperating with said support-moving means for indicating externally of the box which of said resistors are in circuit.
7. A precision variable resistance device for high frequency alternating current measurements comprising a plurality of movable supports, a group of units carried by each of said supports, the units of each group having different resistance but substantially equal spurious resistance, and means for varying the resistance of the device while maintaining constant its spurious impedance comprising conductors of fixed length and position, and means for moving each of said supports to include individually a unit from each of said groups in circuit with said conductors.

LEO BEHR. 25

CERTIFICATE OF CORRECTION.

Patent No. 2,015,651.

October 1, 1935.

LEO BEHR.

It is hereby certified that error appears in the printed specification of the above numbered patent requiring correction as follows: Page 3, second column, line 54, claim 2, for "a" read an individual; line 57, claim 2, for "an individual" read a; page 4, second column, line 17-18, claim 7, for "resistance" read reactance; line 20, for "impedance" read reactance; and that the said Letters Patent should be read with these corrections therein that the same may conform to the record of the case in the Patent Office.

Signed and sealed this 10th day of December, A. D. 1935.

Leslie Frazer

Acting Commissioner of Patents.
